CLAIM

The ornamental design for a elevated dog food stand, as shown and described.

DESCRIPTION

FIG. 1 is a top perspective view of a elevated dog food stand showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the elevated dog food stand, which form no part of the claimed design.
